UNITED STATES PATENT OFFICE.

LAWRENCE DINKELSPIEL, OF NEW YORK, N. Y.

REINFORCED SCALLOPED EDGING FOR EMBROIDERY.

1,152,713.

Specification of Letters Patent. Patented Sept. 7, 1915.

Application filed December 5, 1914. Serial No. 875,590.

To all whom it may concern:

Be it known that I, LAWRENCE DINKELSPIEL, a citizen of the United States, residing in the city of New York, borough of Manhattan, county and State of New York, have invented a certain new and useful Reinforced Scalloped Edging for Embroidery, of which the following is a specification.

This invention is a reinforced scalloped edging for embroidery, and the object of the invention is to adequately bind the scalloped edge and, at the same time, reinforce said edge so that tearing or ripping is precluded.

It has long been recognized in the art to which the invention relates that, when a piece of scalloped edge embroidery is embodied in an article of apparel, such as a brassière or the like, and excessive strain along said scalloped edge will cause the embroidery to rip or tear at the meeting points of adjacent scallops, *i. e.*, at the weakest point of the free edge of the embroidery. Various expedients have been resorted to in an endeavor to obviate this recognized difficulty, but none of these expedients have proved satisfactory.

The present invention obviates the disadvantage referred to in a simple, inexpensive and efficient manner, and embodies, generally speaking, a plurality of stitches so disposed at the meeting points of adjacent scallops, along the free edge of the embroidery, as to adequately reinforce said free edge at its weakest point.

In the preferred embodiment of the invention, the scalloped edge is over-handed or button-hole stitched to form a properly bound or finished edge. Moreover, at the meeting points between each two successive scallops, the thread, which is utilized to bind the edge, is deflected and worked back and forth adjacent to the notch between the two scallops, and is thereafter employed to tightly bind together the stitching so formed and the binding stitching into a compact, strong reinforcing member. If desired, the thread, after having been utilized to form said reinforcing member, may be led into the interior of the material and worked into the embroidery pattern.

Another object of the invention is to provide a binding and reinforcing member, as specified, which may be made by continuous operation and by machinery, if desired.

Features of the invention, other than those specified, will be apparent from the

following description read in conjunction with the accompanying drawings and appended claims.

In the accompanying drawings, I have 60 illustrated one practical embodiment of the present invention, but the construction shown therein is to be understood as illustrative, only, and not as defining the limits of the invention.

Figure 1 is a face view of a section of scalloped edge embroidery embodying the present invention. Fig. 2 is an enlarged detail, fragmental view of the same, showing diagrammatically the manner in which 70 the thread is manipulated to bind and reinforce the edge of said embroidery, and Fig. 3 is an enlarged section taken on line 3—3 of Fig. 1.

Referring to the drawings, A designates 75 a portion of a strip of embroidered material which, as shown in Fig. 1, is scalloped along one edge B. Edge B is shown as embodying a plurality of comparatively large scallops, each of which is, in turn, divided 80 up into a plurality of small scallops to produce a neat, esthetic design. When a piece of embroidered fabric A is utilized in the formation of a skirt, brassière, or the like, it will be manifest that, when the strip 85 is placed under tension, the greatest strain will come at the narrowest portions thereof, *i. e.*, at the meeting point C of any two successive large scallops, and it is particularly at this point, where excessive strain generally tears the goods, that this invention is aimed.

In mechanically embroidering material, it is common to do so by means of a plurality of synchronously moving needles, each of 95 which simultaneously works the pattern of its respective section of the material. For instance, in Fig. 1, two sections A' A² are shown on either side of the line 3—3. In embroidering these two sections, the two 100 needles which do the work start, *e. g.*, at the right-hand side of their respective sections and work toward the left, *i. e.*, in the design shown, the needle which is to work the pattern on section A² would start at the 105 line 3—3 and work toward the left, along the scalloped edge of the fabric, to bind the same, while the complementary needle would start at the right of the section A' and work to the left.

In Fig. 2, I have illustrated, in greatly enlarged diagrammatic form, a method of

binding the scalloped edge of section A', it being understood that the similar edge of section A² is operated upon in the same manner. A thread D starts at the extreme right 5 of section A' and is worked in a substantially vertical manner, as shown, up and down along the entire edge of the scallop, preferably in the form of button-hole stitches d. The vertical stitches are positioned 10 very closely together and are continued in section A' to the line 3—3. At this point, the binding of the scalloped edge ceases, and the next operation is to reinforce the notch between the adjacent scallops. 15 As shown in Fig. 2, thread D, on its last vertical stitch, is deflected laterally and carried in a substantially horizontal direction back and forth and, at the same time, downwardly to the notch between the two adjacent scallops of the sections A' and A², to 20 form stitches e. The stitches e are positioned closely together and overlie the stitches d, adjacent line 3—3 in section A'. It will be understood, moreover, that the 25 needle which is employed to work section A² has previously bound the scalloped edge of said section adjacent line 3—3, so that, when stitches e are applied, they will overlie stitches d of both section A' and A². 30 and tightly bind down the same, thereby reinforcing the fabric at its weakest point. After having carried stitches e to the notch between the adjacent scallops to tightly bind down stitches d, thread D is brought to the 35 notch at line 3—3 and thereafter a series of substantially vertical stitches f are made, for the purpose of tightly binding down stitches e. Stitches f extend upwardly to the uppermost stitch e, and, at the completion 40 of this upward stitching, a close, firm network is formed adjacent the meeting point of the two adjacent scallops. This reinforcing member is designated in the drawings by the reference numeral F. If 45 it is desired to only face or bind the scalloped edge of the fabric A, the operation for section A' will cease at this point, but, if the body of the fabric is to be embroidered, thread D may be led off into the interior 50 of the fabric and utilized to work the embroidery pattern. It will be understood that, while the foregoing operation is going on in section A', a similar operation is being carried on in section A², and in like manner 55 in the remaining sections of the fabric strip A.

Throughout the foregoing description, I have set forth the manner in which my invention is practised when employed in embroidering fabrics by machinery, but, manifestly, I do not restrict myself to this application, as the threads may be manipulated by hand to produce the same results. In either mode of application, it will be manifest that, when the reinforcing member 60

F has been completed, the fabric will be as strong, if not stronger, at the meeting point of any two adjacent scallops than any other portion of the fabric. Accordingly, the present invention accomplishes the desired 70 end in a simple, inexpensive and efficient manner, and the resulting disposition of the various stitches produces an effect extremely pleasing to the eye and one which harmonizes with the stitches of the embroidery 75 pattern.

While I have illustrated in the drawings stitches of particular form, it will be understood that such showing is for illustrative purposes, only, and does not define the 80 limits of the invention.

It will be noted, from Fig. 2 of the drawings, that the stamped line x, which marks the upper edge of the binding, is offset a short distance adjacent the point of meeting 85 of two adjacent scallops, as at x'. In binding the edge, the stitches d are carried along the edge, the upper points of said stitches coming to the line x, but, at that portion of the binding adjacent the meeting point of 90 the two scallops, the stitches d extend only to the line x'. By binding in this manner, a small offset is produced at the inner edge of the binding, so that, when the reinforcing stitches e are applied, their opposite ends 95 will come flush with the binding, and the symmetry of said binding is thus preserved. I do not care to restrict myself to this feature, although it is, manifestly, advisable to so manipulate the thread, since, were the 100 binding not offset as described, the reinforcing stitches e and the consequent reinforcing member F would extend beyond the inner edge of the binding, and said inner edge thereof would not be continuous. The most 105 artistic effects would not, therefore, be produced. It is thus preferable to employ the invention as shown.

The reinforcing member hereinbefore described is illustrated in the drawings in its 110 most practical embodiment, i. e., that embodiment wherein the operation of forming the reinforcing member finishes with a plurality of tying-down stitches in angular relation to the stitches which mainly form the 115 reinforcing member. I wish it understood, however, that I do not restrict myself to the use of these tying-down stitches, as, if desired, these may be omitted.

Having thus fully described the invention, 120 what I claim as new, and desire to secure by Letters Patent, is:

1. A fabric provided on one of its edges with a notch, a thread worked along said edge into a plurality of stitches to form a 125 binding for said edge, a plurality of reinforcing stitches disposed in angular relation to the binding stitches and adjacent the notch at the edge of the fabric, said reinforcing 130 stitches overlying the binding stitches adja-

cent said notch for the purpose of reinforcing the edge of the fabric at its notched portion, and a plurality of tying stitches positioned in angular relation to the stitches overlying the binding stitches for tightly securing the binding stitches and the reinforcing stitches to one another and to the fabric.

2. A fabric provided with a scalloped edge, a thread worked along said scalloped edge to form substantially parallel stitches for the purpose of binding the scalloped edge of the fabric, said thread being diverted at the meeting point of two adjacent scallops to form a plurality of stitches in angular relation to, and overlying, the binding stitches whereby the fabric is reinforced at the meeting point of two adjacent scallops, and said thread also forming a plurality of tying stitches arranged in angular relation to the reinforcing stitches.

3. A fabric provided with a scalloped edge, a thread worked along said scalloped

edge to form substantially parallel stitches for the purpose of binding the scalloped edge of the fabric, said thread being diverted at the meeting point of two adjacent scallops to form a plurality of stitches in angular relation to, and overlying, the binding stitches whereby the fabric is reinforced at the meeting point of two adjacent scallops, and said thread also forming a plurality of tying stitches arranged in angular relation to the reinforcing stitches and passing from the tying stitches into the interior of the fabric and formed into a plurality of stitches forming the embroidery design. 25 30 35

In testimony whereof I have signed my name to this specification in the presence of two subscribing witnesses.

LAWRENCE DINKELSPIEL.
